UNITED STATES PATENT OFFICE.

HUDSON H. BUBAR, OF NEW YORK, N. Y.

INDUSTRIAL FURNACE.

Application filed August 10, 1923. Serial No. 656,656.

To all whom it may concern:

Be it known that I, HUDSON H. BUBAR, a citizen of the United States of America, residing at city of New York, county of 5 Kings, and State of New York, have invented a new and useful Industrial Furnace, of which the following is a specification.

My invention relates particularly to apparatus for roasting ore and analogous operations.

The main object is to provide a construction having complete mechanical control of the roasting and oxidation (when required) from the time the material enters until it is 15 discharged. In carrying out this invention I preferably employ the combination of a reverberatory furnace and a preheater arranged to discharge the material on to a horizontal hearth. Within the furnace I 20 provide a rabbler which is adapted to travel back and forth within the furnace and thoroughly mix up and turn over the material being treated. Details of construction and mode of operation will be understood from 25 the following description and the accompanying three sheets of drawings.

Fig. 1 is a horizontal section and plan showing parts of the apparatus more or less diagrammatical.

Fig. 2 is a corresponding longitudinal vertical sectional view on the plane of the line 2—2 of Fig. 1.

Fig. 3 is a transverse sectional view on the plane of the line 3—3 of Fig. 2 on a somewhat larger scale.

Fig. 4 is a side view of one form of rabbler.

Fig. 5 is a fragmentary plan view of part of the rabbler looking in the direction of 40 the line 5—5 of Fig. 6.

Fig. 6 is a fragmentary edge view of the parts of the rabbler looking in the direction of the line 6—6 of Fig. 4.

Figs. 7, 8 and 9 are detail views of a modified form of rabbler.

Fig. 10 is a side view showing cooling bars.

Fig. 11 shows details of the mechanism for adjusting and moving the cooling bars on the line 11—11 of Figure 12.

Fig. 12 is a detail view of parts of the mechanism shown in Fig. 11 and taken on the line 12—12 thereof.

The substance to be roasted is fed into the preheater through the hopper and chute at

1 in Fig. 2, is gradually carried through the preheater to point of discharge at 2 where it is dropped through flue 3 to hearth 4 being gradually carried forward by rabbler 5 to point of discharge 6 where it falls on inclined cooling plates 7 and thence to conveyor 8 where it is finally discharged from the furnace.

Air is drawn in through conduits 9, and passes between the cooling bars and the material thereon and also through the fire box 10 and over the wall 11 and back through the chamber 12. The gases pass out flue 3 around the preheater and out the chimney or stack 13. The circulation in the 65 hearth not only keeps the hearth cool but pre-heats the air going to the furnace. The hearth 4 may also have cooling passages, 9'. It should be understood that although the furnace is shown as arranged for coal, gas 70 or oil may be provided for if desired within the spirit of my invention.

The preheater for the ore or other material consists of a rotating steel cylinder 14 in a chamber 15 formed in a fire brick shell. Baffles 16 and 17 may be provided to provide a tortuous passage for the waste gases so as to preheat the material to as high a temperature as possible or to the temperature required. Supplementary flue 18 or by-pass 80 may be provided if desired with a damper 19 or control element. The spring of the arch 20 is preferably designed so as to reflect directly on the hearth.

The rabbler has two side frames 22 provided with wheels 23 and 24 which travel on tracks 25 and 26 beneath the side edges of the hearth. Track 26 and wheel 24 at one side may be so designed as to permit side ways expansion and contraction of the rabbler. Upper guides 27 and 28 may be provided for preventing the rabbler from rising.

The sides 22 of the carriage, the shaft 29 and blades 30 and 31 of the rabbler are all hollow to permit circulation of air for cooling the rabbler parts and in some cases for oxidizing the material to be treated. The blades may have outlets 32 for admitting air directly to the ore or other material.

Air is supplied to the rabbler through flexible hose 33 adapted to be wound on air drum 34. An equalizing spring and ratchet 35 may be employed to keep a uniform tension on the drum and hose. The drum

is driven with the shaft 36 which is connected to the rabbler drive so that the rabbler and hose will move synchronously.

The rabbler carriage is moved back and forth by the chains 37 at any desired speed and it may be reciprocated for a part of the length of the hearth at any place on the hearth or the entire length. The preferred form of rabbler is rotated by chain 38 from shaft 39 and gears 40 driven in any suitable way for instance by a stationary rack or chain 40'. The blades on the rabbler are staggered or offset so as to sweep every part of the hearth and turn over and mix the material thoroughly.

The normal position of rest for the rabbler is in the chamber 41 beyond the flue 3. When the rabbler starts toward the fire box it rotates idly over the hearth, the shaft 39 being provided with a one-way automatic clutch 39'. When it starts back on the return trip the shaft 29 and blades start rotating clockwise as viewed in Fig. 2 thereby mixing and oxidizing the material while forcing it a certain distance along toward the discharge incline 7.

The rabbler shown in Figs. 7, 8 and 9 has two sleeves or shafts 42, 42' with fingers 43, 43'. These shafts 42 and 42' are connected by a link 44 so that they may be rocked by a rod 45 and crank 46. The fingers 43 and 43' may be lifted at any time by means of the rod 45. These rabbler fingers act like the teeth of a rake when the rabbler moves toward the fire box and carry along some of the material toward the inclined discharge 7.

When the material falls upon the cooling plates it is partially cooled and oxidized by the admission of air and discharged on the conveyor 8 or onto another hearth like 4 where it may be again treated.

The inclined plates 47 are supported near the middle of their ends by rollers 48 and are also provided with extensions 49 which are hinged to bars 50. Bars 50 are supported by rollers 51 carried by bars 52. Bars 50 have forks 53 to receive cranks 54 on shaft 55 so that when shaft 55 is rotated or oscillated the bars 50 are reciprocated and the plates 47 vibrated back and forth to aid the movement of the ore or other material being treated.

The bar 52 is supported by cams 56 so that the bar 52 and its rollers 51 and the bar 50 can be raised and lowered. The raising and lowering of the bar 50 tilts the plates 47 about the rollers 48 so as to increase or decrease the opening 57 between adjacent plates and thus admit more or less air as desired to the hot material.

In cases where the introduction of air direct to the ore or other substance is disadvantageous the rabbler would have no discharge outlets but the cooling air could be

admitted into the rabbler through one side and out the other or out through some part of the rabbler where the air will not come in direct contact with the material being treated. It should also be understood that air may be admitted through the rabbler to the ore or shut off when desired, for instance the air can be admitted during part of the rabbler stroke and cut off during the remainder. Although I have referred to the invention as particularly adapted to roasting ores, it should be understood that the apparatus is also useful for drying or otherwise treating various other materials.

What I claim is:

1. A roasting furnace comprising an extended stationary hearth for treating material with the products of combustion, a rabbler movable longitudinally of said hearth, a pre-heater for discharging material upon one end of said hearth, and means for passing the gases from the material around the outside of the pre-heater without contact with the material in the pre-heater.

2. A roasting furnace comprising a longitudinally extending hearth having air cooling passages, supporting tracks mounted beneath the opposite edges of said hearth, side frames extending above and below the opposite sides of said hearths, each side frame having wheels supported on said tracks, a rotating rabbler carried by said side frames above said hearth, and means for moving said frames along said tracks and rotating said rabbler above said hearth.

3. In a furnace, a longitudinally extending hearth, a rabbler rotatably mounted to travel back and forth over said hearth, said rabbler having air passages, a drum, flexible hose wound on said drum and connected to said rabbler, and means for moving said rabbler back and forth.

4. A furnace comprising an extended hearth, a rabbler mechanism movable along said hearth and having a frame with an air passage, and a rotating rabbler member having blades with air outlets in the ends of said blades.

5. In a furnace, a rotating pre-heater having means for admitting ore at one end, and means for discharging ore from the other end, a roasting hearth having one end arranged beneath the discharge end of said pre-heater, means for passing gases from the material being roasted around the outside of the pre-heater and automatic means for moving the ore along said hearth.

6. In a furnace, a pre-heater having a passage through which ore is discharged into the furnace, and through which hot gases pass out around the pre-heater, and a supplemental controlled passage leading from the furnace to said pre-heater.

7. In a furnace, a series of inclined discharge plates for the roasted ore, and means for moving said plates back and forth and up and down.
- 5 8. In a furnace, a series of inclined ore discharging plates, means for adjusting them vertically and means for reciprocating said plates.
- 10 9. In a furnace, an inclined cooling grate having discharge plates for roasted ore with controllable openings therebetween.
- 15 10. In a furnace, a hearth, a rotating rabbler having blades movable along said hearth, and means for admitting air through said blades for directly controlling the oxidization of the substances being roasted.
- 20 11. In a furnace, a hearth, a rabbler having rotatable blades movable along said hearth, and means for admitting air through said blades for controlling the oxidization of the substances being roasted.
- 25 12. In a furnace, a pre-heater having a passage through which ore is discharged into the furnace and through which hot gases pass out around the pre-heater, and a supplemental passage leading from the fur-
- nace to said pre-heater and means for rabblering the ore in the furnace.
13. In a furnace, a pre-heater having a 30 rotating drum and divisional partitions and baffles for causing heated gases to pass around said drum and means for controlling the flow of gases.
14. In a furnace, a series of inclined discharge plates for the roasted ore, and means for separating said plates.
15. In a furnace, an inclined cooling grate having plates for roasted ore and having controllable openings therebetween 40 and a transverse discharge conveyer at the lower end.
16. In a furnace, an extended hearth, a rotatable rabbler movable above said hearth and having air outlets, a power driven 45 drum and air hose wound on said drum and connecting said drum and said rabbler.
17. In a roasting furnace, a movable air cooled rabbler, an air drum, a flexible air hose on said drum connecting the drum and 50 rabbler and spring actuated means for maintaining tension on the hose.

HUDSON H. BUBAR.
